(57) **CLAIM**

The ornamental design for a heel counter, as shown and described.

DESCRIPTION

FIG. 1 is a rear perspective view of a heel counter, shown in use on an article of footwear;

FIG. 2 is a rear elevational view of the heel counter shown without the footwear environment;

FIG. 3 is a medial side elevational view thereof;

FIG. 4 is a lateral side elevational view thereof; and,

FIG. 5 is a top plan view thereof.

The broken lines in the drawings show features that form no part of the claimed design.
